UNITED STATES PATENT OFFICE

WILLIAM B. BETTS, OF BINGHAMTON, NEW YORK

COIN CONTROLLED MECHANISM

Application filed May 7, 1931. Serial No. 535,768.

This invention relates to a coin controlled mechanism, designed primarily for use in connection with machines for successively vending single cigarettes, but it is to be understood that a coin controlled mechanism in accordance with this invention may be employed in any connection or any type of vending machine for which it may be found applicable, and the invention has for its object to provide, in a manner as hereinafter set forth, a mechanism of the class referred to for controlling the delivery of articles of merchandise from a vending machine.

A further object of the invention is to provide, in a manner as hereinafter set forth, a mechanism of the class referred to, with new and novel means for effecting the automatic division of the coins inserted therein on a predetermined percentage basis and to deliver each division of the coins into a separate compartment located within the casing of the vending machine.

It is customary in the practice of selling articles of merchandise or the like from vending machines, for the manufacturer of the machine or of the manufacturer of the articles of merchandise, or of both, to place the machines in various localities and generally at established business houses or stores, paying a percentage of the money collected by the machine or machines to the proprietors of such business houses for the sale of the goods vended from the machines, for the space occupied by the machine or machines, and for the general supervision and protection afforded the machines by such proprietors. In the present construction of coin controlled mechanisms, the money collected by the same has, in many known instances, been discharged from the mechanism therefrom into a single coin compartment, which necessitates a great amount of time in the counting of the coins at the end of stated periods of operation of the machines and the separation therefrom of the percentage of the total money collected and due the proprietor of the place where the machine is installed, and to provide for the automatic division of the collected coins, to overcome the inconvenience of counting the same is one of the objects of this in-

vention and is attained by structure as hereinafter set forth.

Further objects of the invention are to provide a coin controlled mechanism, in a manner as hereinafter set forth and for the purpose referred to, and which is simple in its construction and arrangement, strong, durable, compact, formed of few parts, thoroughly efficient in its use, conveniently operated for the successive delivery of single cigarettes or other articles of merchandise, and comparatively inexpensive to set up.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation of a vending machine having installed therewith a coin controlled mechanism in accordance with this invention.

Figure 2 is a section on line 2—2 Figure 1. 80

Figure 3 is a section on line 3—3 Figure 2.

Figure 4 is a perspective view looking towards the inner face of the actuating element for the coin delivery mechanism.

Figure 5 is a fragmentary view in side elevation of one of the walls of the vending machine. 85

Figure 6 is an elevation looking towards the outerside of a coin carrier in accordance with this invention.

Figure 7 is a section on line 7—7 Figure 6.

Figure 8 is a section on line 8—8 Figure 5.

Figure 9 is a section on line 9—9 Figure 6.

Referring to the drawings in detail, 1 generally indicates a vending machine having a discharge slot 2 near the bottom of its front through which the article is vended. The delivering mechanism of the machine is carried by and operated by a shaft 3 which is 100

journaled in supports 4, 5 arranged within the housing of the machine. The shaft 3 has journals 6, 7 mounted respectively in keyhole shaped openings 8, 9 formed respectively in supports 4, 5. The machine includes a coin receiving chamber 10 and a coin receiving chamber 11 arranged below the chamber 10. The coin intake for the chamber 10 is indicated at 12 and which is formed in the support 5. The coin intake 12 consists of a rectangular slot disposed at an inclination with respect to support 5 and having its bottom wall beveled as at 13 and with the bevel extending downwardly at an inclination 14 from the outer face to the inner face of support 5. The journals 6, 7 are arranged in the reduced portions of the openings 8, 9 and shaft 3 projects outwardly from support 5 and has a reduced portion 14 upon which is mounted loosely a shifting element 15 for shaft 3 to provide for the operation of the delivery mechanism. Positioned below the element 15 is the coin entrance 16 for the coin receiving chamber 11 and such entrance 16 is provided by a slot formed in a partition member 17' which is arranged within the housing of the machine and provides the bottom of the chamber 10 and the top of the chamber 11. The coin entrance 16 is positioned between the support 5 and one of the side walls of the housing.

Fixed to the shaft 3 and bodily movable therewith, as well as being interposed between the journal 7 and the reduced portion 14 of shaft 3 is a coin carrier 17 which is formed with a series of U-shaped coin receiving pockets and as illustrated by way of example the carrier is set up with five pockets, four of which are indicated by reference character 18 and the other one by the reference character 19. The edge of each pocket 17 is formed with a laterally extending retaining lug 20 for the coin. The lugs 20 extend inwardly and are of less thickness than the width of the edges from which they project. The edge of pocket 19 is beveled as at 21 and the bevel extends in the same direction as the bevel 13 and is adapted to align with the latter to form a continuation thereof for a purpose to be presently referred to. The lugs 20 retain the coins 22 in the pockets 18 until the coin in a pocket 18 is discharged therefrom and such discharge happens when a pocket 18 has its open end oppose the coin entrance 16. The lugs 20 coat with the support 5 during the rotation of the carrier for the purpose of retaining the coins in the pockets 18 and are flush with the inner face of carrier 17. The coin from the pocket 19 is automatically discharged therefrom when the bevel edge of such pocket registers with the bevel edge 13 of the entrance slot 12 for the chamber 10. By the arrangement of carrier as set forth, one coin out of every five will be discharged in chamber 10 and the

other four coins discharged into chamber 11 which provides an automatic division of the coins without the necessity of counting them.

The depth of the coin receiving pockets is such as to provide for the coin to project beyond the mouth of the pocket. See Figure 6. The projecting portion of the coin is adapted to couple the shifting element to the shaft for the purpose of operating the latter to provide for the actuation of the delivery mechanism to vend cigarettes. The shifting member 15 comprises a body portion 23 in the form of a circular disc provided with a central aperture 24 for loosely mounting on the reduced portion 14 of the shaft 3. The disc 23 is of greater diameter than the carrier 17 and abuts against the outer face of the latter. The inner face of body portion 23 is formed with an arcuate flange 25 which registers with the outer edge of disc 23. Projecting from the inner face of the body portion of disc 23 is an apertured lug 26 which extends through an arcuate slot 27 provided in the support 5. Attached at one end to the partition 17 and its other end to the lug 26 is a controlling spring 27' for the shifting member 15.

The front wall of housing 1 has a coin entrance slot 29 which registers with the upper end of an inclined coin chute 30 secured to the outer face of support 5 and which has its lower end open at the edge of body portion 23 of shifting element 15. An arcuate flange 31 opposes the body portion 23 and is arranged forwardly of shaft 3. Flange 31 provides a bearing for a lever 32 which is integral with the body portion 23 and projects forwardly therefrom and also through a slot 33 provided in the front wall of the housing 1 below the coin entrance slot 29.

The opening 24 in disc 23 is of the keyhole type and it is disposed in a different manner than the openings 8 and 9, that is to say the smaller portion of opening 24 is arranged above the larger portion whereas the smaller portion of openings 8 or 9 is arranged below the larger portion.

As the invention resides solely in the coin controlled mechanism for operating the operating shaft of the delivery mechanism of a vending machine, it is thought unnecessary to describe the elements not referred to, as such elements do not form a part of the coin controlled mechanism.

When the shifting element 15 is in inactive position, the flange 25 is arranged rearwardly of that coin pocket positioned at the top of the coin carrier. After a coin has been inserted into the machine and has entered the coin pocket positioned at the top of the coin carrier, the lever 32 is moved downwardly carrying the body portion 23 of element 15 therewith whereby the forward edge of flange 25 will engage with the coin 22 and shift the coin carrier which in turn will shift

the shaft 3 and provide for the operation of the delivery mechanism. The operative movement of the element 15 is arrested by the lug 26 engaging the top wall of slot 28 and the return movement of element 15 will be arrested by lug 26 engaging the bottom wall of the slot 28. The return movement of the element 15 is had through the medium of its controlling spring 27'. The coins which are mounted in the pocket 19 will be discharged through the slot 12 into chamber 10, through the action of the beveled edge of pocket 19 and beveled edge of slot or opening 12. The coins in the other pockets of the carrier will fall therefrom, exteriorly of the support 5 and pass through the entrance 16 into the chamber 11.

What I claim is:—

1. In a coin controlled mechanism, the combination with a support provided with a slot and a shaft mounted in and projecting outwardly from said support, said slot having a beveled wall, of a coin carrier mounted on the projecting portion of said shaft and bodily moving therewith, controlling means for said shaft, said carrier opposing said support and provided with a series of coin receiving pockets, one of said pockets having its edge beveled to provide for the discharge of a coin therefrom through said slot, at a point in advance from which the coins are discharged from the other of said pockets, when the beveled edge of such pocket registers with the beveled wall of said slot, said slot being of rectangular contour and inclining downwardly from its rear towards its outer end and having the bevel of its wall inclining away from the coin carrier to form a continuation of the beveled edge of the pocket when the latter registers with said beveled wall portion of the slot.

2. In a coin controlled mechanism, the combination with a support provided with a slot and a shaft mounted in and projecting outwardly from said support, said slot having a beveled wall, of a coin carrier mounted on and bodily movable with said shaft, controlling means for said shaft, said carrier opposing said support and provided with a series of coin receiving pockets, one of said pockets having its edge beveled to provide for the discharge of the coin therefrom through said slot, at a point in advance from which the coins are discharged from the other of said pockets, when said beveled edge registers with the beveled wall of said slot, said slot being of rectangular contour and inclining downwardly from its rear towards its front and having the bevel of its wall extending in a direction downwardly away from the coin carrier to form a continuation of the beveled edge of said pocket when said beveled edge registers with the beveled wall of the slot, said slot radially disposed with respect to the axis of the carrier and partly concealed by the latter, and each of said pockets other than said beveled edge pocket having extending of its edge a coin retaining lug to prevent the passage of the coin through said pocket.

with respect to the axis of the carrier and partly concealed by the latter.

3. In a coin controlled mechanism, the combination with a support provided with a slot and a shaft mounted in and projecting outwardly from said support, said slot having a beveled wall, of a coin carrier mounted on the projecting portion of said shaft and bodily moving therewith, controlling means for said shaft, said carrier opposing said support and provided with a series of coin receiving pockets, one of said pockets having its edge beveled to provide for the discharge of a coin therefrom through said slot, at a point in advance from which the coins are discharged from the other of said pockets, when the beveled edge of such pocket registers with the beveled wall of said slot, said slot being of rectangular contour and inclining downwardly from its rear towards its outer end and having the bevel of its wall inclining away from the coin carrier to form a continuation of the beveled edge of the pocket when the latter registers with said beveled wall portion of the slot, and each of said pockets other than said beveled edge pocket having extending of its edge a coin retaining lug to prevent the passage of the coin through said pocket.

4. In a coin controlled mechanism, the combination with a support provided with a slot and a shaft mounted in and projecting outwardly from said support, said slot having a beveled wall, of a coin carrier mounted on and bodily movable with said shaft, controlling means for said shaft, said carrier opposing said support and provided with a series of coin receiving pockets, one of said pockets having its edge beveled to provide for the discharge of the coin therefrom through said slot, at a point in advance from which the coins are discharged from the other of said pockets, when said beveled edge registers with the beveled wall of said slot, said slot being of rectangular contour and inclining downwardly from its rear towards its front and having the bevel of its wall extending in a direction downwardly away from the coin carrier to form a continuation of the beveled edge of said pocket when said beveled edge registers with the beveled wall of the slot, said slot radially disposed with respect to the axis of the carrier and partly concealed by the latter, and each of said pockets other than said beveled edge pocket having extending of its edge a coin retaining lug to prevent the passage of the coin through said pocket.

In testimony whereof, I affix my signature hereto.

WILLIAM B. BETTS.
